UNITED STATES PATENT OFFICE.

CARL HERMAN CLAUSEN, OF SOLVESBORG, SWEDEN, ASSIGNOR TO PATENTAKTIE-BOLAGET CENTRALSMÖRJNING, OF SOLVESBORG, SWEDEN, A CORPORATION OF SWEDEN.

FORCED-LUBRICATION APPARATUS.

Application filed March 13, 1925, Serial No. 15,409, and in Sweden July 3, 1924.

The subject of this invention is a driving and guiding device for the pump pistons in forced lubrication apparatus and the object of the invention is to simplify this device to 5 the greatest possible extent, without depreciating the function or the effect of the apparatus, and thus to obtain a cheap apparatus.

It is already known to drive a pump piston by the means of an eccentric or cam disc which by the intermediary of a fork-shaped part acts upon the piston or its rod, thereby causing a reciprocating motion of the piston. It is further known to construct valveless pumps, in which the pump cylinder is alternately brought in communication with suction and pressure conduits by rotating the piston about its longitudinal axis and providing the same with connection channels, 20 so that the piston in addition to its ordinary function also acts as rotary valve. In these known devices however very complicated mechanical contrivances for obtaining the double (the reciprocating and the rotary) motion of the piston had to be adopted, and the chief object of the invention is to accomplish a far reaching simplification of the driving device. This, according to the invention, is obtained in two manners perfectly alike as to the principle but somewhat departing from each other with respect to the mechanical execution, viz:—

(a) By arranging in the apparatus a driving cylinder disposed eccentrically relatively to the axis of rotation, the eccentricity of said cylinder causing the reciprocating motion of the piston, while grooves arranged in this cylinder inclining toward the axis of rotation and in cooperation with a crank-pin 40 or the like fitted to the pump piston bring about the rotary motion, and

(b) By arranging in the apparatus a driving cylinder of whatever external form, which may be co-axial in relation to the axis of rotation, and providing this cylinder with obliquely disposed grooves for causing the rotary motion of the pistons in the same manner as before, but which grooves are provided with a bottom eccentrically disposed in 45 relation to the axis of rotation and preferably in the form of a cam disc, so that this groove bottom on account of its position relatively to the pump piston will cause the reciprocating motion of the latter. In this

case the crank-pin connected to the piston and engaging the groove may preferably be substituted by a mechanical equivalent, viz, an eccentric.

Thus the difference between these two mechanical embodiments of the invention is 55 this that in the former case it is the eccentricity of the driving cylinder which brings about the reciprocating motion of the pistons, while in the latter case the bottoms of the grooves are causing same motion, 60 and here the external form of the cylinder and its disposition relatively to the axis of rotation is of no influence for the function of the pump.

The invention is more fully explained in 70 the following description reference being had to the accompanying drawings, in which Figs. 1 and 2 show a forced lubrication apparatus adapted for four lubricating places, and executed in accordance with the embodiment indicated above as (a), in a transversal and longitudinal section respectively. Fig. 3 shows on a larger scale a detail of the driving cylinder in a transversal section, and Fig. 4 shows likewise on a larger scale 75 a pump piston in a lateral view. Figs. 5 and 6 show a horizontal projection and a transversal section respectively of Fig. 4. Figs. 7 and 8 show in a like manner as in Figs. 1 and 2 a forced lubrication apparatus 80 executed in accordance with the embodiment indicated above as (b).

In the embodiment according to Figs. 1 to 6 the numeral 1 designates an oil container, in which is journalled a driving shaft 2 connected to a suitable source of power and in which there are further arranged oil pumps 3 of a number in agreement to the number of lubricating places, said oil pumps having suction channels 4 embouching with in the container near its bottom and pressure channels 5 passing through the wall of the container and adapted to be connected in a suitable manner with oil conduits.

Each pump has a fixed guide, preferably a rod 6, an arcuated strap 7 being displaceably arranged thereon, the one branch of the strap embracing with a fork-shaped part 8 the pump piston immediately below a flange or head 9 fixed thereto, and the other branch of the strap provided with a screw 10 having a corresponding flange or a head 11. On the driving shaft 2 there is eccentrically ar-

ranged a cylinder 12 disposed between the heads 9 and 11, and when rotating the driving shaft the pump pistons receive by the intermediary of the eccentric cylinder 12 a 5 reciprocating motion, the length of stroke of which is variable by adjusting the screws 10. The heads 9 are provided with a crank-pin 13 pointing toward the shaft 2, said crank-pin extending into an endless groove 14 in 10 the cylinder 12 disposed obliquely relatively to the axis of the driving shaft, so that by this means the pump pistons in addition to the above stated reciprocating motion also receive a rotary motion.

15 In order that the pumps may work in a theoretically correct manner, that is to say that the inlet and outlet of the pump cylinders register correctly with the suction and pressure channels respectively, it is of im- 20 portance, that the rotation of the piston takes place at the two ends of its stroke or, in other words, in those positions of the piston, in which this has no appreciable axial motion. To accomplish this, the 25 grooves 14 have two straight parts disposed at right angles relatively to the axis of the shaft in two different planes (see Fig. 2) and these straight groove parts are arranged relatively to the eccentricity of the cylinder 30 12 in such a manner, that they correspond to resting periods in the axial motions of the pistons. The straight groove parts are arranged at such a distance axially from each other that they correspond to a rotation of the pistons of 90° , in consequence whereof the suction inlet and pressure outlet of the pump cylinder become disposed diametrically opposite to each other, so that they may be executed in form of a bore-hole 35 40 passing straight through the cylinder, as disclosed in Fig. 1, and by this means the manufacture is furthermore simplified. The straight groove parts are connected with each other with oblique groove parts, which 45 cause the rotation of the pump piston, the one in the one direction and the other in the other direction.

Though the grooves being carried out in the manner above described it should be 50 clear, that for reason that the oblique groove parts cannot actually be arranged accurately axially along two opposite generatrices for the cylinder 12, the function of the pumps will not be theoretically correct, if the cylinder 55 12 has a true eccentric form, for in such case the pistons receive just as well an axial displacement simultaneously with the rotation. To avoid this, the cylinder 12 is not made accurately eccentric but receives 60 a cross-sectional form as disclosed in Fig. 3. This form has arisen in the following manner:—The outer mantle of the cylinder has been divided up in four bows opposing each other in pairs, of which the two bows 65 15 and 16 corresponding to the greatest and

smallest eccentricity are true circular arcs having the axis of the shaft 2 as centre, while the two remaining bows 17 and 18 which connect and smoothly go over into the first named bows are preferably also circular 70 arcs but having a centre eccentrically disposed in relation to the axis of the shaft 2. The bows 17 and 18 need not necessarily be circular arcs but may be constituted of other 75 affined curves. The bows 17 and 18 correspond to the straight parts of the grooves 14 and the bows 15, 16 to the oblique parts, and it should be clear, that on account of the described eccentric or, more correctly 80 expressed, cam form of the cylinder 12 the pistons are not subjected to any axial displacement during their rotation.

The pump pistons (Figs. 4 and 6) are provided with an axial channel 19 opening into the pump cylinder and two channels 85 20 and 21 emerging from the channel 19 at an angle of 90° between. When rotating the piston, the channels 20 and 21 are alternately brought in communication with the suction and pressure channels 4 and 5 respectively. In order to keep the communications open during the axial displacement of the piston axial grooves are arranged in 90 the outer surface of the piston at the embouchments of the channels 20 and 21.

95 It should be obvious, that the embodiment above described may be varied in many respects. Thus, for each pump one may arrange a separate driving cylinder provided with grooves, which cylinder, for example 100 in form of a collar, is pushed upon and fixed to the shaft in a suitable manner, for example with set screws. The manufacture of the apparatus in this manner embodies several advantages, because the driving shaft 105 and the members connected thereto may more easily be adapted to agree with varying members of pumps in each apparatus and further, in apparatus having a large number of pumps, the load may be evenly distributed 110 by placing the eccentricities at different angles in relation to each other. Further the forks 7 need not be displaceably arranged on the rods 6 but could be securely fastened thereto, if the rods for example are displaceable 115 in guides (bore-holes), and the part 8 may entirely embrace the piston or its rod.

In the embodiment shown in Figs. 7 and 8 like reference numerals as in Figs. 1 to 6 are used for like parts. A convenient number of pumps 3 arranged in the oil container 1, are driven from the common shaft 2 by means of straps 7—8 embracing the shaft. These straps are displaceably mounted on guide rods 6 and at their upper part 120 provided with heads 11 adjustable by means of screws 10 for controlling the length of stroke of the pump piston and thus the effect of the pump.

125 Instead of having the above described 130

crank-pin 13 the pistons in this case are provided with a head in the form of a disc 22 at right angles and eccentrically disposed relatively to the axis of the piston, and it is this eccentric head that directly causes the rotation of the piston, which latter thus simultaneously serves as rotary valve. By this means the manufacture of the piston becomes further simplified.

10 To accomplish the rotation of the pistons the eccentric head 22 engages in grooves 23—corresponding to the grooves 14 in the embodiment first described—and these grooves are obliquely disposed in relation to 15 the axis of driving shaft in a cylinder 24, corresponding to the cylinder 12. The outer form of this cylinder 24 is immaterial for the invention but is shown in the drawing to be of cylindrical form. The bottom of 20 the grooves 23 is eccentric relatively to the axis of the driving shaft or has the form of a cam disc having the same properties as the cam-shaped driving cylinder 12 above described, and it is this eccentric groove bottom that causes the axial displacement of 25 the pistons when rotating the shaft.

What I claim and desire to secure by Letters Patent is:—

1. A driving device for forced lubrication apparatus comprising a pump with a pump piston, a driving shaft, a cylinder mounted eccentrically thereon and formed with an endless groove in part in a plane at right angles to the axis of the shaft and in part 30 in a plane oblique to said axis, a strap partly surrounding the cylinder, one end of the strap cooperating with the pump piston to rotatably carry the latter, a crank carried by the pump piston beyond the strap with the crank 35 pin engaging in said groove in the cylinder, and means for guiding the strap against 40 other than a reciprocating movement in a

line substantially parallel to the movement of the pump piston.

2. A driving device for a forced lubrication apparatus comprising a pump with a pump piston, a driving shaft, a cylinder mounted eccentrically thereon and formed with an endless groove in part in a plane at right angles to the axis of the shaft and in part 45 in a plane oblique to said axis, a strap partly surrounding the cylinder, one end of the strap cooperating with the pump piston to rotatably carry the latter, a crank carried by the pump piston beyond the strap with 50 the crank pin engaging in said groove in the cylinder, means for guiding the strap against other than a reciprocating movement in a line substantially parallel to the movement of the pump piston, and means carried 55 by the end of the strap opposite that end connected to the piston to bear upon said cylinder in substantial alignment with the piston.

3. A driving device for a forced lubrication apparatus comprising a pump, a pump piston therein having a head, a driving shaft, a cylinder mounted eccentrically on the driving shaft and formed with a groove having a portion at right angles to the axis 60 of the shaft and a portion oblique to such axis, a strap guided for reciprocating movement in a line substantially parallel to the movement of the piston and having its respective ends above and below the cylinder 65 in substantial alignment with the piston, the lower end of the strap being connected to the piston below the head thereof to rotatably carry the piston, a crank pin on the piston head adapted to seat in said groove, and an adjustable head carried by the upper end of the strap to bear on the cylinder. 70

In testimony whereof, I have signed my name to this specification.

CARL HERMAN CLAUSEN.
